DRIVING MECHANISM FOR SCREW DRIVERS
AND DRILLSThomas Samuel Barbeau, Ancaster, Ontario,
Canada

Application May 15, 1940, Serial No. 335,350

8 Claims. (Cl. 74—56)

My invention relates to driving mechanism for screw drivers and drills and an object of my invention is to devise an improved means for actuating the screw driver or drill.

5 A further object is to construct a driving mechanism which can be operated by both hands.

A still further object is to originate a construction which will be simple and effective and which can be manufactured in quantities at a reasonable cost.

With the above and other objects in view which will hereinafter appear as the specification proceeds, my invention, in its preferred embodiment, consists of the construction and arrangement all 15 as hereinafter more particularly described and illustrated in the accompanying drawing in which:

Fig. 1 represents a front elevation of a screw driver constructed according to my invention.

20 Fig. 2 is a side elevation thereof, and

Fig. 3 is an enlarged section taken through the line 3—3 (Fig. 1).

Like characters of reference indicate corresponding parts in the different views of the drawing.

In the device as illustrated which shows my driving mechanism applied to a screw driver, 1 represents a rectangular frame with one end 2 detachable. Said frame is provided at its ends 30 with bearings 3 and 4 which receive the ends of a spindle 5 which carries a worm 6, the lower end of the spindle 5 protruding through the bearing 3 and being provided with a chuck 7 adapted to receive a screw driver 8 or alternatively a bit or 35 twist drill.

The side members of the rectangular frame 1 serve as guides for the slides 9 extending therebetween, said slides being disposed on opposite sides of the rectangular frame 1 and having on 40 the outer face of each spaced apart bearings 10 through which pivot pins 11 formed on a plate 12 secured to the inner end of a handle 13 extend. Each of said handles has a shaft 14 extending freely and axially inwardly therethrough and 45 freely through the slide being provided on its inner end with a disc 15 adapted to engage a side surface of the flight of the worm 6.

The outer end of each shaft 14 has an enlargement 16 located in a bore 17 in the outer end of each handle 13, which bore is closed by a screw plug 18 and a spring 19 is interposed between each screw plug and the enlargement 16 on the corresponding shaft 14.

50 In order to hold the handles 13 in either of two positions one bearing 10 of each pair is provided

with a toothed quadrant 20 with which a pawl 21 on the handle 13 is designed to engage.

So that the slides may be operated in unison some adequate means must be provided for interconnecting them. As illustrated this means may 5 comprise cables 22 and 23 attached to the opposite ends of the slides 9 and passing respectively over pulleys 24 and 25 on the top and bottom ends of the frame 1.

The top end 2 of the rectangular frame 1 is 10 provided with an extension 26 carrying a breast pad 27.

Assuming that the parts of the mechanism are positioned as illustrated in the drawing with the axes of the shafts 14 inclined to the axis of the 15 worm 6 and the left and right hand discs 15 (Fig. 2) respectively engaging the upper faces of the worm flights and resiliently held thereagainst by the springs 17 urging the shafts 14 inwardly, 20 the tool is held by the operator grasping the handles 13 with the breast pad 27 in engagement with his breast and the chisel shaped end of the screw driver 8 inserted into the slot in the screw to be driven (not shown). By pushing down on the right hand handle its connected disc 15 is 25 rotated and presses down on the worm flight turning the worm 6 in the direction of the arrow (Figs. 1 or 2) and consequently rotating the screw driver 8 so that the screw is driven in. Simultaneously by pulling up on the left hand handle 13 its connected worm owing to bearing resiliency on the worm flight is retracted and rides over the flights of the worm until the slide reaches its uppermost position on the frame 30 when by pushing down on the left hand handle its connected disc 15 takes up the drive of the worm and the right hand handle is pulled up 35 causing its connected disc to slide over the flights of the worm.

40 Thus by alternately pushing down and pulling up on the respective handles the worm and its attached screw driver is substantially continuously driven in the direction of the arrow.

45 To reverse the direction of rotation of the worm it is only necessary to swing the handles until the handles (Fig. 2) engage the lower surfaces of the worm flights when by repeating the above reciprocal operation of the mechanism the worm and its attached screw driver are rotated in the reverse direction to that above indicated.

50 From the above description it will be apparent that a simple and effective means is provided for driving a screw driver, or bit or drill substituted therefor. In fact the mechanism described and 55 illustrated may be employed for any other pur-

pose where it is desired to translate reciprocating power into rotary motion. Furthermore instead of reciprocating the slides manually by the handles they could be reciprocated mechanically.

5 For instance, the mechanism might be employed for driving a bicycle or tricycle or for propelling a small boat.

What I claim as my invention is:

1. Means for translating reciprocating applied

- 10 power into rotary motion comprising a frame, a rotatable worm journalled longitudinally therein and including a power take off thereon, a slide longitudinally reciprocable on the frame, a shaft journalled on the slide with its axis at an angle 15 to the axis of the worm and axially slidale, a disc on the inner end of the shaft and adapted to engage a side surface of the flight of the worm, a spring urging the shaft and disc inwardly, and means for reciprocating the slide whereby the 20 disc rotates the engaged worm during the stroke of the slide in one direction and slides over the flight of the worm without rotating it during the reverse stroke of the slide.

2. The invention as claimed in claim 1 where- 25 in means is provided on the slide for reversing the angularity of the shaft with respect to the worm whereby the disc attached to the inner end of the shaft engages the opposite side face of the flight of the worm and rotates such worm 30 and the attached power take off in a reverse direction upon reciprocation of such slide.

3. Means for translating reciprocating applied power into rotary motion comprising a frame, a rotatable worm journalled longitudinally 35 therein and including a power take off thereon, a slide longitudinally reciprocable on one side of the frame, a second slide longitudinally reciprocable on the opposite side of the frame, means between the slides for interconnecting them for 40 actuation in unison but in opposite directions, a shaft journalled on each slide with its axis at an angle to the axis of the worm and axially slidale, a disc on the inner end of each shaft and adapted to engage a corresponding side face of 45 the flight of the worm, a spring urging each shaft and disc inwardly, and means for reciprocating each slide whereby the disc on its shaft rotates the engaged worm during the stroke of such slide in one direction and slides over the flight 50 of the worm without rotating it during the reverse stroke of such slide.

4. The invention as claimed in claim 3 where- 55 in means is provided on each slide for reversing the angularity of its shaft with respect to the worm whereby the disc attached to the inner end thereof engages the opposite side of the flight of the worm and rotates such worm and the attached power take off in a reverse sense upon reciprocation of such slide.

- 60 5. A device comprising a longitudinal frame, a rotatable worm longitudinally journalled therein and including a tool gripping chuck, a slide longitudinally reciprocable on the frame, a handle including a rotatable shaft longitudinally 65 slidale therein, means for attaching the handle to the slide so that the axis of the shaft is disposed at an angle to the axis of the worm, a disc

on the inner end of the shaft adapted to engage a side face of the flight of the worm, and a spring in the handle adapted to urge the shaft and disc inwardly, said handle being adapted to be manually reciprocated whereby the disc rotates the engaged worm during the stroke of the attached slide in one direction and slides over the flight of the worm without rotating it during the reverse stroke of the slide.

6. A device comprising a longitudinal frame, 10 a rotatable worm longitudinally journalled therein and including a tool gripping chuck, a slide longitudinally reciprocable on the frame, a handle including a rotatable shaft longitudinally slidale therein, means for attaching the 15 handle to the slide so that the axis of the shaft is disposed at an angle to the axis of the worm, a disc on the inner end of the shaft adapted to engage a side face of the flight of the worm, a spring in the handle adapted to urge the shaft 20 and disc inwardly, said handle being adapted to be manually reciprocated whereby the disc rotates the engaged worm during the stroke of the attached slide in one direction and slides over the flight of the worm without rotating it during 25 the reverse stroke of the slide, and means incorporated in the means for attaching the handle to the slide for swinging and locking the handle in a position whereby its shaft is disposed in reverse angularity to the worm so that the disc 30 on the inner end of the shaft engages the opposite side face of the flight of the worm.

7. A device comprising a longitudinal frame, a rotatable worm longitudinally journalled 35 therein and including a tool gripping chuck, a slide longitudinally reciprocable on one side of the frame, a second slide longitudinally reciprocable on the opposite side of the frame, a handle for each slide including a rotatable shaft longitudinally slidale therein, means for at- 40 taching each handle to its slide so that the axis of its shaft is disposed at an angle to the axis of the worm, a disc on the inner end of each shaft engageable with the corresponding side face of the flight of the worm, a spring in each 45 handle adapted to urge its shaft and disc inwardly, and means for connecting the slides so that they slide in unison but in opposite directions, said handles being adapted to be manually reciprocated whereby each disc rotates the 50 engaged worm during the stroke of the attached slide in one direction and slides over the flight of the worm without rotating it during the reverse stroke of the slide.

8. The invention as claimed in claim 7 where- 55 in the means for attaching the handle to its slide each comprises bearings on the slide, trunnions on the handle inserted into the bearings, said handle and its shaft and disc being capable of being swung into a position wherein the axis 60 of the shaft is disposed in reverse angularity to the axis of the worm and the disc on its inner end engaging the opposite side of the flight of the worm, and means for alternatively locking the handle in each angular position.
